UNITED STATES PATENT OFFICE.

HARLEY STAMP, OF PHILADELPHIA, PENNSYLVANIA.

SUPPORTING DEVICE.

1,273,550.

Specification of Letters Patent.

Patented July 23, 1918.

Application filed February 26, 1918. Serial No. 219,337.

To all whom it may concern:

Be it known that I, HARLEY STAMP, a citizen of the United States, residing at Philadelphia, in the county of Philadelphia and State of Pennsylvania, have invented certain new and useful Improvements in Supporting Devices, of which the following is a specification.

One object of my invention is to provide an efficient and comfortable supporting device for use on the human body and which will serve as a brace and support for the abdomen and when used on men will serve to support the scrotum and adjacent parts of the body.

Another object of my invention is to make the several parts adjustable so that they can be adjusted from time to time to suit the comfort of the wearer and also that the device can be regulated to fit persons of various sizes and shapes.

These objects, and other advantageous ends which will be described hereinafter, I attain in the following manner, reference being had to the accompanying drawings in which—

Figure 1 is a perspective view illustrating my invention,

Fig. 2 is a fragmentary sectional elevation taken centrally through a portion of my invention, and

Fig. 3 is a fragmentary perspective view showing a modification in certain of the parts of my invention.

Referring to the drawings, 1 represents an abdominal band which is preferably made comparatively wide and of flexible material, such as strong duck or other webbing or cloth. This band is provided with an adjusting buckle 2 whereby it can be made of larger or smaller diameter according to the size of the person and also to suit the comfort of the wearer. As illustrated the band 1 includes an elastic insert 3 which may be made of fabric including rubber or the like which will slightly yield due to the movement of the wearer. When the elastic insert is employed it is preferable that it should be made of strong material since the function of the abdominal band is to hold in and firmly embrace the body adjacent the abdomen and around the back and sides of the body so that elastic material

which would not assist or which would be detrimental to the desired function of the abdominal band should not be employed.

Two shoulder straps 4 and 5 are preferably made of inelastic material and have their rear ends 6 secured to the rear of the abdominal band 1. These straps 4 and 5 extend directly upward over the respective shoulders and then downwardly in the front so as to cross each other, as clearly shown in Fig. 1. These two straps 4 and 5 are secured together at their point of crossing 65 in the front and have adjusting buckles 7 which permit them to be tightened or loosened when the device is being worn on a person's body.

The front end portions of the straps 4 and 5 are secured to links 8 which in turn are secured to doubled tabs 9, the latter being sewed to the front portion of the abdominal band 1. The links 8 permit easy movement and a flexible connection between 75 the straps 4 and 5 and the abdominal band 1.

A strip 10 of material which is elastic lengthwise is, at its upper end, secured between and to the shoulder straps 4 and 5 at their crossing point 11 and depends centrally from said crossing point and is secured at its lower end to the front of the abdominal band 1. The elastic strip 10 includes two sections 12 and 13, as illustrated in Figs. 1 and 2, and these sections 80 are connected by a link 14 of the same general character as the links 8 above described. The lower end of the section 12 is looped through the link 14 and is provided with an adjusting buckle 15 whereby the strip 10 90 can be lengthened or shortened so as either to reduce or increase its tension.

Another strip 16, which is preferably made of a softer material than the strip 10, is elastic lengthwise and at its upper 95 end is secured between and to the lower end of the elastic strip 10 and the central front portion of the abdominal band 1. The strip 16 depends centrally from the abdominal band and at its lower end is attached to the 100 upper front portion of a pouch or sack 17 adapted to support the scrotum and adjacent parts of the body.

Two strips 18 and 19, preferably made of inelastic material, are secured to the top of 105 the pouch 17 adjacent the opposite sides

thereof and these strips extend at an angle which flares upwardly. In other words, the strips at their lower end portions are closer together than at their upper end portions.

5 These upper end portions are secured to the front of the abdominal band 1, as clearly shown in Fig. 1.

The rear bottom portion of the pouch 17 has secured to it two straps 20 and 21.

10 These straps extend rearwardly between the legs of the wearer and then upwardly from the rear of the wearer and at their upper ends are supported by the abdominal band 1 at positions slightly in advance of the middle of the opposite sides of the abdominal band. The straps 20 and 21 extend through adjusting buckles 22 and 23 on the sides of the band 1.

By the construction of my invention as above described, the shoulder straps 4 and 5, by being crossed in the front, serve to firmly hold and embrace the portion of the abdomen above the band 1. The result of crossing these shoulder straps is that it provides a brace substantially in the form of an inverted V which extends upwardly from the abdominal band. This in itself provides an efficient abdominal support. By providing the additional centrally extending elastic strip 10 which depends centrally from the shoulder straps, at their point of crossing, to the front of the abdominal band 1, a median elastic support is provided for the portion of the abdomen positioned below the point of crossing of the shoulder straps and between the lower portions of said shoulder straps. In fact the tension of the elastic strip 10 and also the elastic strip 16 serves to slightly raise the abdomen and thereby relieves strain on that portion of the body and provides a secure and efficient support. Furthermore, the tension exerted by the elastic strips 10 and 16 serves to firmly hold the pouch 17 up against the body so as to properly support the scrotum and the adjacent parts.

Referring to Fig. 3, I have shown a construction very much similar to the construction shown in Figs. 1 and 2 with the exception that instead of providing the strip 10 made up entirely of elastic material I provide a strip 10^a which is made up of an inelastic section 12^a and an elastic section 13^a. This difference in arrangement provides a structure which will have less elasticity or will yield less than the construction of the strip 10 above described. In all other respects the elements in Fig. 3 are similar to those described in connection with Figs. 1 and 2 and I have, therefore, given similar parts corresponding reference numerals.

While I have described my invention as taking a particular form, it will be understood that the various parts of my inven-

tion may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A device of the character described including an abdominal band; shoulder straps crossing in the front and attached to the band; and a central elastic member secured to the abdominal band at the front and to the shoulder straps, substantially as described. 75

2. A device of the character described including an abdominal band; shoulder straps crossing in the front and secured to the band both at the front and rear thereof; and an elastic strip depending centrally from the shoulder straps at their point of crossing and being secured at its lower end to the abdominal band, substantially as described. 85

3. A device of the character described including an abdominal band; shoulder straps crossing in the front and secured to the band both at the front and rear thereof; an elastic strip depending centrally from the shoulder straps at their point of crossing and being secured at its lower end to the abdominal band; and means for adjusting the length of said central elastic strip, substantially as described. 95

4. A device of the character described including an abdominal band; shoulder straps crossing in the front and secured to the band both at the front and rear thereof; an elastic strip depending centrally from the shoulder straps at their point of crossing and being secured at its lower end to the abdominal band; and means for adjusting said straps between their crossing point and the abdominal band, substantially as described. 100

5. A device of the character described including an abdominal band; shoulder straps crossing in the front and secured to the band both at the front and rear thereof; a pouch positioned below the abdominal band; and elastic means depending centrally from said shoulder straps at their crossing point, said means at its lower end being secured to said pouch, substantially as described. 110

6. A device of the character described including an abdominal band; shoulder straps crossing in the front and secured to the band both at the front and rear thereof; a pouch positioned below the abdominal band; elastic means depending centrally from said shoulder straps at their crossing point, said means at its lower end being secured to said pouch; and strips extending from said pouch at an angle flaring upwardly and at 120

their upper ends secured to said abdominal band, substantially as described.

7. A device of the character described including an abdominal band; shoulder straps crossing in the front and secured to the band both at the front and rear thereof; a pouch positioned below the abdominal band; elastic means depending centrally from said shoulder straps at their crossing point, said means at its lower end being secured to said pouch; and straps connected to said pouch at its rear lower end, said straps at their opposite ends being secured to the abdominal band, substantially as described.
- 10 8. A device of the character described including an abdominal band; shoulder straps connecting said band both at the front and rear; and elastic means attached to the front

of said abdominal band and supported by the shoulder straps above said band, substantially as described.

9. A device of the character described including an abdominal band; shoulder straps connecting said band both at the front and rear; elastic means attached to the front of 25 said abdominal band and supported by the shoulder straps above said band; and means for adjusting said shoulder straps, substantially as described.

In testimony whereof I have signed my 30 name to this specification in the presence of two subscribing witnesses.

HARLEY STAMP.
